UNITED STATES PATENT OFFICE.

ARTHUR J. BRAUER, OF ST. LOUIS, MISSOURI.

CADDY-BAG.

1,118,469.

Specification of Letters Patent. Patented Nov. 24, 1914.

Application filed September 18, 1913. Serial No. 790,386.

To all whom it may concern:

Be it known that I, ARTHUR J. BRAUER, a citizen of the United States, and residing at St. Louis, in the State of Missouri, have invented certain new and useful Improvements in Caddy-Bags, of which the following is a specification.

This invention relates to caddy bags used for the reception of golf clubs and golf balls.

Some of the objects of this invention are to provide a caddy bag having a novel bottom construction, a novel top construction, a novel handle, and constructed and arranged to have not only great strength and durability, but also present a neat and pleasing appearance.

Another object is to provide a novel and convenient compartment adapted to receive the golf balls.

Further objects will appear from the detail description taken in connection with the accompanying drawing, in which:

Figure 1 is a front elevation of a caddy bag embodying this invention, the carrying strap being cut away to expose the handle, Fig. 2 is a side elevation, Fig. 3 is a section on the line 3—3 Fig. 4, Fig. 4 is a section on the line 4—4 Fig. 3, and Fig. 5 is a section on the line 5—5 Fig. 2.

Referring to the accompanying drawing, 10 designates the body which is preferably formed of canvas or the like, stitched together to form an elongated tubular structure. Strips 11, 12 and 13, preferably of leather, are stitched to and extend along the body. The upper end of the body has stitched thereto a leather edging 14 which is turned outwardly over a ring 15 and 40 stitched in position. The strips 11 and 12 form pockets to receive steel stays 17, which extend nearly to the ring 15 and are secured at their upper ends by rivets 18 passing through the edging 14, the stays, the body 10, and the covering strips 11 and 12. A leather band 16 extends around and is stitched to the body and to the turned over edging so as to cover up the turned over portion of this edging and the ends of the 50 stays. This forms an upper edge having not only the required strength and rigidity, but also presenting a pleasing appearance.

The lower end of the body has a leather edging 19 which is turned outwardly over 55 a ring 20 and secured by a line of stitches

as the top edging; and the stays 17 extend down nearly to the bottom ring 20 and are secured by rivets 21 passing through the edging, stays, body and strips. A wide leather band 22 is stitched to the body covers and the turned over portion of the edging 19. The stays 17 extend in and along the pockets formed by the strips, and outside of the body 10 above the top of the band 22; the body 10 is however, slit transversely at the top edge of the band 22, and the stays extend downwardly along the body inside of the body from this point. This construction permits the line of stitching at the top of the band 22 to pass through the strips 11 and 12 so as to make a tight seam and fit at this point, thereby effectually preventing entrance of grass and dirt as the bag is dredged over the ground. It will be understood that this seam is made before the stays are inserted. The bottom consists of a flanged leather disk 23 secured in position by a line of stitches passing through the flange, the edging 19, the body 10 and the band 22.

The bag has a false bottom comprising a flanged leather disk 24 secured in position by a line of stitches passing through the flange, body and band 22. This forms a bottom compartment, and this bottom compartment has a side aperture 25 closed by a flap 26 stitched at one end to the band 22 and provided at the other end with a tongue engaging a buckle 27 on the band. The compartment is adapted to receive a number 30 of golf balls, which can be inserted and removed through the aperture 25, the bottom of which is flush with the bottom 23.

A strap 28 having a buckle 29 is provided to clamp the golf clubs in position in the 95 bag. A carrying strap 30 is secured at its upper end to the upper end of the bag while its lower end engages a buckle 31 on the strip 13. The strip 13 has secured thereto a reinforced handle 32, which is sewed and 100 riveted to the stay at 33 and 34. This forms a smooth and stiff handle which may be readily grasped to manipulate the bag.

It will thus be seen that the invention accomplishes its objects. A bag is formed 105 which not only presents a neat and pleasing appearance but possesses also great strength and durability. Both the top and bottom are reinforced by rings which are entirely concealed. The bottom will not only retain 110

its shape while it is being dragged over the ground, but will form a firm support for the ends of the golf clubs. The handle 32 not only presents a smooth grip, but this handle is of such rigid construction that the bag may be readily manipulated.

It is obvious that various changes may be made in the details of construction without departing from the spirit of this invention, 10 and it is therefore to be understood that this invention is not to be limited to the specific construction shown and described.

Having thus described the invention what is claimed is:

15 1. A caddy bag comprising a tubular body, an edging attached to the upper end of said body, a rigid ring inclosed by said edging, said edging being turned outwardly over said ring, stays extending along said body and attached to said edging, and a band surrounding the end of said body and inclosing the joint between said body and said edging.

20 2. A caddy bag comprising a tubular body, an edging attached to the bottom end of said body, a rigid ring inclosed by said edging, said edging being turned outwardly over said ring, a bottom located within said body and positioned above said ring, and a band surrounding the end of said body and

inclosing the joint between said body and said edging.

25 3. A caddy bag comprising a tubular body, an edging attached to the bottom end of said body, a rigid ring inclosed by said edging, said edging being turned outwardly over said ring, stays extending along said body, a bottom located within said body and positioned above said ring, said bottom being attached to said stays, 40 and a band surrounding the end of said body and inclosing the joint between said body and said edging.

4. A caddy bag comprising a tubular body, an edging attached to the bottom end 45 of said body, a rigid ring inclosed by said edging, said edging being turned outwardly over said ring, a bottom located within said body and positioned above said ring, said bottom having a downwardly extending flange positioned within and inclosing the edging, and a band surrounding the end of said body and inclosing the joint between said body and said edging.

In testimony whereof I affix my signature 5: in the presence of these two witnesses.

ARTHUR J. BRAUER.
